CLAIM

The ornamental design for a backpack inner compartment as shown and described.

DESCRIPTION

FIG. 1 is a perspective view of a backpack inner compartment showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a perspective view of a backpack inner compartment showing my new design, in a closed state.

The dash-dot-dot broken lines represent stitching on backpack inner compartment and are included in the claimed design. The dash-dash broken lines show environment and form no part of the claimed design.

1 Claim, 9 Drawing Sheets
